UNITED STATES PATENT OFFICE.

JOHN S. NOEL, OF GRAND RAPIDS, MICHIGAN.

ACETYLENE-GENERATING APPARATUS.

Application filed December 24, 1919. Serial No. 347,117.

To all whom it may concern:

Be it known that I, JOHN S. NOEL, a citizen of the United States of America, residing at Grand Rapids, in the county of Kent 5 and State of Michigan; have invented certain new and useful Improvements in Acetylene-Generating Apparatus; and I do hereby declare the following to be a full, clear, and exact description of the invention, 10 such as will enable others skilled in the art to which it appertains to make and use the same.

This invention relates to an acetylene generator. It is a primary object and purpose 15 of the present invention to make a generator in which, when the carbide falls into the water, it falls within a cylindrical casing or mixing chamber, the upper end of which always passes a distance into the lower end 20 of the gas bell, and the lower end of which while open in construction is soon closed by sediment deposited from the carbide so that no gas is lost by escape from the water around and outside of the gas bell, all of the 25 gas being generated within said mixing chamber and going directly therefrom into the gas receiving bell. This provides insurance against loss of gas and against the necessity of completely charging all of the 30 water within the generator and super-saturating the same so that gas will arise therefrom to the gas bell. A further object and purpose of the invention is to provide a novel cooling chamber at the bottom of the 35 generator into which the gas is led after filtration and in which it is held for a time before passing outwardly to be used. The cooling chamber is a reservoir to hold the outgoing gas for a time before use, it being 40 cooled while thus held. A still further object of the invention is to provide a generator in which the sediment deposited from the carbide may be very conveniently removed without the necessity of, at the same 45 time, removing the whole or a major part of the charged water in which the sediment is deposited, this tending to economy in operation of the generator as a considerable amount of carbide is consumed in saturating 50 fresh water before any gas rises therefrom for use.

All of these various features of utility to

gether with many others not specifically stated at this time, appear and the constructions for attaining the same are fully disclosed in the following description taken in connection with the accompanying drawings, in which;

Fig. 1 is a vertical section through the complete assembled generator.

Fig. 2 is a similar section, the cover for the outer casing or the well, the gas bell and the carbide holder being removed for the ready insertion of the sediment removing pumping outfit.

Fig. 3 is a horizontal section taken on the line 3—3 of Fig. 1; and

Fig. 4 is a fragmentary perspective and sectional view of the lower part of the generating apparatus.

Like reference characters refer to like parts in the different views of the drawings.

The generator comprises the usual outer casing or well 1 of sheet metal which has a bottom 2, the upper end of the well being normally closed by a removable cover 3. This well is cylindrical in form, preferably. In the bottom of the well a hollow cooling chamber or reservoir is positioned, being comprised of two arms 4, and an additional longer arm 5 disposed at angles to each other as shown in Fig. 3. On this cooling reservoir member a cylindrical casing 6 of sheet metal is positioned being open at both ends and resting at its lower end on the arms 4 and 5. Pipes 7 thread at their lower ends into the arms 4 and 5 and extend upwardly above the casing 6, having threaded connection at their upper ends with a channel shaped ring 8 in which filtering material 9 is placed.

The carbide holder 10 rests on the ring 8. It is provided with a downwardly and inwardly inclined bottom 11 of substantially funnel shaped form on which the carbide 12 is carried. An opening is made at the lower end of the funnel and a rod 13 extends vertically through this opening and through the top of the carbide holder having a valve head 14 at its lower end which in upper position closes the opening in the bottom of the carbide holder and prevents the escape of carbide. A lever 15 is pivotally mounted between its ends on the top of the carbide

holder and at one end has pivotal connection to the rod 13, the opposite end being equipped with a weight 16, the effect of which is to normally elevate the valve 14 and prevent the escape of carbide. A gas bell 17 having a closed upper end 18, is located within the well 1 and is freely movable up and down within the same. The diameter of the bell 17 is greater than that of the carbide holder 10, the ring 8, and of the casing 6 so that it passes down over the same as shown in Fig. 2. The lower end of the bell extends into the water which is normally kept at a level slightly below that of the upper end of the casing. It is evident that the weight of the gas bell normally tends to carry it to a lower position such that the top 18 will strike the upper end of the rod 13 thereby moving the rod downwardly and permit the escape of carbide into the water from which gas is generated and returned to the bell. Upon generation of a sufficient amount of gas the bell is lifted above the rod 13 and the escape of carbide to the water stopped. When the gas is to be used it passes from the bell through the filter 9 and down the pipes 7 into the spaces within arms 4 and 5 from which it passes outwardly through the outlet pipe 19 attached at the end of the longer arm 5, from which pipe the gas may be taken and used for any desired purpose. With the passage of gas from the bell it lowers and again operates the rod 13 to allow the passage of carbide to the water and the generation of additional gas. Accordingly, as long as there is carbide in the carbide holder the supply of gas within the bell 7 remains practically constant. From the carbide a sediment is deposited in the water. This sediment is indicated at 20 and in a short time fills the spaces between arms 4 and 5 and closes the lower end of the cylindrical casing 6. Thereafter no gas can go to the water outside of the casing 6 and there is no rising and loss of gas from the water between the walls of the gas bell and the well 1. This sediment must be removed at times and I have shown the method of and apparatus for removal in Fig. 2. The cover 3 is removed and the gas bell 17 and carbide holder 10 taken from the well. A pipe 21 provided with a well known type of pump 22 at its upper end is lowered into the well. The pump is secured to a platform 23 which rests on the upper edges of the well. At the lower end of the pipe 21 a conical shaped member 24 is fastened and the same embeds itself substantially into the sediment. The sediment may be freely pumped from the bottom of the casing 6 by operating the pump 22 and the greater portion thereof removed without affecting or removing the water; in fact, very little or no water will be removed as

the sediment is removed, and this is of value as the water should be left in the well if possible, inasmuch as several pounds of carbide are required to charge and saturate fresh water before gas will escape therefrom to the gas bell. In removing the sediment it is not desirable to remove all of it, particularly that which is deposited between the arms 4 and 5 of the cooling reservoir. This sediment left, seals the bottom of the casing 6 and precludes any waste of gas through escape from the water outside of the casing 6.

This construction of generation is comparatively simple and has proven very practical and serviceable in use and operation. The invention is defined in the appended claims and I consider myself entitled to all modifications in structure which fall within the scope of said claims.

I claim:

1. A device of the character described comprising an elongated vertically positioned well, a flat hollow reservoir in the bottom of the well comprising a plurality of connected arms, pipes threaded unto the arms and extending upwardly therefrom, a casing surrounding the pipes within the well and resting at its lower end on the arms of the reservoir, a carbide container supported at the upper end of the pipes, a gas bell located within the well and covering the carbide container and extending downwardly beyond the upper end of the casing, means for automatically feeding carbide from the container as the supply of gas within the gas bell diminishes, said gas from the gas bell passing through the pipes into the hollow reservoir, and an outlet pipe connected to one of the arms of the reservoir at the end thereof outside of the casing and gas bell, substantially as and for the purposes described.

2. In a device of the character described, an elongated vertically positioned well, a hollow cooling reservoir located in and resting on the bottom of the well and comprised of a plurality of connected radiating arms, one of which is longer than the others, pipes connected to the arms and extending upwardly therefrom, a hollow ring at the upper end of the pipe to which said pipes are connected, a carbide container supported by the ring, a gas bell located within the well and passing downwardly over and covering the carbide container and extending a distance below the same, and an outlet pipe connected to the outer end of the longer arm of the reservoir and passing upwardly in the well between the side thereof and the gas bell, substantially as described.

3. In a device of the character described, an elongated vertically positioned well, a hollow reservoir resting on the bottom of the well and comprising a plurality of radial arms through which gas generated passes

and is held and cooled before use, a casing open at both ends and resting at its lower end on said arms of the reservoir, a carbide container located directly over the upper end of the casing, whereby carbide delivered therefrom drops within the casing and sediment from the carbide fills the

spaces between the arms and lower part of the casing, and an outlet pipe connected to one arm of the reservoir at a point outside 10 of the casing, substantially as described.

In testimony whereof I affix my signature.

JOHN S. NOEL.
